UNITED STATES PATENT OFFICE.

JOHN AMBROSE DAVIS, OF NACO, ARIZONA, ASSIGNOR OF ONE-FOURTH TO M. R. MILLER, OF NACO, ARIZONA, ONE-FOURTH TO J. M. MILLER, OF VACAVILLE, CALIFORNIA, AND ONE-FOURTH TO TRAYHARNE DAVIS, OF OAKLAND, CALIFORNIA.

CARBURETER.

1,091,426.

Specification of Letters Patent. Patented Mar. 24, 1914.

Application filed October 21, 1912. Serial No. 726,852.

To all whom it may concern:

Be it known that I, JOHN A. DAVIS, a citizen of the United States, residing at Naco, in the county of Cochise and State of Arizona, have invented new and useful Improvements in Carbureters, of which the following is a specification.

This invention relates to carbureters, and particularly to that type known as "spray carbureters."

The object of the present invention is to provide a simple, compact and efficient carbureter, so constructed that rapid vaporization and greater homogeneity of the final mixture will be produced.

Another object of the invention is to provide simple outside adjusting means by which the carbureter may be adjusted for various speeds to secure perfect ignition and steady running.

The invention consists in certain novel constructions, combinations and arrangements of parts, all of which will be herein-after more particularly set forth and described in the following specification and drawings, in which—

Figure 1 is a vertical, longitudinal section of the outside casing partly broken away. Fig. 2 is a cross section on line X—X, Fig. 30 1. Fig. 3 is a perspective view of the throttle valve head. Fig. 4 is a perspective view of the throttle valve tube. Fig. 5 is a longitudinal, central, vertical section. Fig. 6 is a perspective view of the gasolene valve adjusting means. Fig. 7 is a perspective view of the air-valve, spring tension adjusting means. Fig. 8 is a fragmentary view showing the gasolene level adjusting means. Fig. 9 is a detail view showing the position of 40 stop 13.

In the accompanying drawings A indicates the float valve or receiving chamber which is provided with a central inlet valve 2, automatically controlled by a float 3 connected to the inlet valve 2 by the usual connecting links and levers 4.

5 indicates the main mixture chamber which is connected with a valve-controlled, air inlet chamber 6 through a carbureting tube 7. The carbureting tube 7 is slidably and turnably mounted in an annular sleeve or hub 8, carried by or forming part of the cover portion 9 of the air inlet chamber. The carbureting tube 7 is provided with a

lug 10, so positioned on the tube as to register with a thread or groove 11, formed in the lower portion of the sleeve 8. The tube is also provided with a stop 12 which engages with a shoulder 13, formed on the sleeve 8 for the purpose of preventing the lug 10 from passing out of engagement with the thread portion 11. The operation of the stop 12 and the shoulder 13 is further explained by referring to Figs. 1 and 4 which show the sleeve 8 as being provided with a shoulder 13 with which the pin 12 engages to prevent the lug 10 from passing out of engagement with the thread portion 11; the pin being free to move in the opposite direction when the tube is turned to the upper position as the sleeve is sufficiently cut away to prevent a free return movement of the pin 12. The upward movement of the tube is limited by the length of the thread portion 11 when the lug 10 reaches the end of 75 the thread. The upper end of the tube is provided with slots 13^a engageable with lugs 14 forming part of a throttle valve 15. A portion of the throttle valve 15 projects through the wall of the mixture chamber 5 80 and is provided with a square portion 16, upon which is secured a throttle valve lever 17. The lugs 14 forming a part of the throttle valve are provided with an annular ring 18 for the purpose of holding and guiding the tube 7.

The position of the tube 7, with relation to the head portion of the throttle valve, may be adjusted by turning the throttle valve lever 17 in one direction or the other, 90 whichever the case may be. The turning of the lever 17 in the direction of arrow b will cause the lug 10 to climb up the thread portion 11 and force the tube up against the upper portion of the throttle valve head, 95 thus decreasing the port area or discharge opening of the throttle valve when it is desired to cut down the mixture. Motion to turn the tube is transmitted through the throttle valve head and lugs 14 which engage with the slots 13^a in the tube.

One of the important advantages of this invention is the construction of the spray nozzle for the purpose of discharging gasolene in as finely divided a state as possible. 105 In any one carbureter the perfection of vaporization is proportioned to the fineness with which the liquid is broken up at the

2

nozzle. The shortness of the time within which vaporization must be completed is what causes the above factor of fineness of division to enter. Thus it is readily seen 5 that the finer the fuel division at the nozzle, the more rapid and complete will be the vaporization and the greater the homogeneity of the final mixture. The spray nozzle 19 here shown, is constructed with this object 10 in view and is provided with a puppet valve 20, the lift of which is controlled by a threaded adjustable stop 21. The position of the stop 21 may be controlled by the thumb wheel 22, which is provided with a 15 rod 23 extending through the center of the carburetor. This is provided with a square portion 24 at its lower end which registers with a similar socket portion 25 in the head of the adjustable stop 21, thus making it 20 possible to regulate and adjust the position of the stop from the outside.

During operation, air is admitted to the carburetor through a suitable number of perforations 26. These perforations or openings 25 are formed in the cover 9 and are normally closed by a spring seated valve 27. The air when entering through the openings 26 follows the path indicated by the arrows *c* and reaches the main chamber through 30 the mixture tube 7, this causing the air to concentrate and rush by the spray nozzle tip 19. The passage of air at this point forms sufficient vacuum to raise the valve 20 and admit the gasoline. The puppet valve is 35 provided with a flat head which breaks the jet of the discharging gasoline and forces it out radially in all directions in the form of a fine spray. The amount of gasoline admitted at this point is controlled by the position of the adjustable stop 21, or in other words, by the lift of the valve 20; the stem of the valve being tapered or otherwise formed to admit more or less gasoline in proportion to the lift of the valve.

45 The quantity of mixture that an engine will take varies greatly with the speed. At low speeds the mixture should be richer than at high speed, this being due to the fact that at low speeds more heat is lost 50 through the cylinder walls and also considerable compression is lost by leakage. At high speeds the compression is higher, due to less leakage and less loss of heat. Therefore, unless the mixture be leaner at high 55 speed, there might be danger of pre-ignition. With this object in view I have provided means for creating more or less spring tension on the air valve 27. This means consists of a strap having an upper collar portion 28 and a lower collar portion 29. Upon the collar 29 is seated a disk 30 which holds the spring up against the valve 27. The upper collar 28 on the strap is carried by a hollow threaded rod 31 which passes 60 through the throttle valve head, and the

throttle valve head is threaded to receive the rod 31; the rod 31 being provided with an adjusting screw 32 secured in any suitable manner, or as here shown by a keyway, to the upper end of the rod. By turning the 70 adjusting screw it will be possible to raise and lower the rod 31 within the carburetor, which in turn will lift the strap and spring-supporting disk 30, thus causing more or less tension upon the spring. From this it 75 can be seen that when the engine is running at low speeds, the amount of air passing through the carburetor will be much less than at higher speeds. The spring being adjusted to a certain tension will only allow 80 a certain proportion of air to pass the valve, which proportion is determined to give the best results at normal speed.

By the construction here shown a simple and compact carburetor is produced in which the float is arranged concentrically with the spray nozzle. This construction eliminates disturbance of the fuel level, with respect to the nozzle, which otherwise would be caused by any inclination of the car. 90 Another advantage accomplished by this construction is the position of the spray nozzle with relation to the passage of air through the carburetor, giving it an opportunity to produce the highest efficiency and 95 best results. The mixture after passing and discharging from the upper end of the throttle valve tube passes in the direction of the arrows *d*, striking the upper portion of the mixture chamber where it is deflected 100 and given a swirling motion before passing out of the discharge opening 34.

For the purpose of adjusting the spray nozzle with relation to the gasoline level within the float chamber, or vice versa, I 105 have provided means for raising or lowering the air inlet chamber within the float chamber. This is accomplished by providing slanting slots 36 in the float chamber and screws 37 by which the air chamber may be locked to the float chamber when the desired adjustment has been made. The adjustment is accomplished by turning the float chamber circumferentially with relation to the air chamber which will cause the 110 slots to either climb or recede on the lock screws 37 on the air chamber.

The carburetor is neat in appearance, simple and compact in construction, and may be easily adjusted and controlled by the means 115 positioned outside of the casing. The materials and finish of the several parts are such as experience and judgment of the manufacturer may dictate.

I wish it understood that various changes 120 in form, proportions and minor details of construction may be resorted to within the scope of the appended claims, and that I 125 do not wish to limit myself to the specific 130 design and construction here shown.

Having thus described my invention, what I claim and desire to secure by Letters Patent is—

1. A carbureter comprising a mixture chamber, a valve-controlled air inlet chamber, a float chamber surrounding the air inlet chamber, a throttle valve in the mixture chamber having a plurality of ports, a carbureting tube connecting the throttle valve with the air inlet chamber, means for adjusting said tube with relation to the ports in the throttle valve to increase or decrease the port area, a vertically disposed, automatically controlled fuel inlet valve in the float chamber, a vertical spray nozzle connecting the float chamber with the air inlet chamber centrally positioned with relation to the float in the float chamber and with relation to the carbureting tube, a valve mounted in the spray nozzle to control the discharge of fuel from the nozzle, and means for controlling the lift of the valve.

2. A carbureter comprising a mixture chamber, an air inlet chamber, a plurality of ports through which the air is admitted, a spring-actuated valve closing said ports, means for adjusting the tension of said spring-actuated valve, a float chamber surrounding the air inlet chamber, a throttle valve in the mixture chamber having a plurality of ports, a carbureting tube connecting the throttle valve with the air inlet chamber, means for adjusting said tube with relation to the ports in the throttle valve to increase or decrease the port area, a vertically disposed, automatically controlled fuel inlet valve in the float chamber, a vertical spray nozzle connecting the float chamber with the air inlet chamber centrally positioned with relation to the float in the float chamber and with relation to the carbureting tube, a valve mounted in the spray nozzle to control the discharge of fuel from the nozzle, and means for controlling the lift of the valve.

3. A carbureter comprising a mixture chamber, an air inlet chamber, a plurality of ports through which the air is admitted, a spring-actuated valve closing said ports, means for adjusting the tension of said spring-actuated valve, a float chamber surrounding the air inlet chamber, a throttle valve in the mixture chamber having a plurality of ports, a carbureting tube connecting the throttle valve with the air inlet chamber, means for adjusting said tube with relation to the ports in the throttle valve to increase or decrease the port area, a vertically disposed, automatically controlled fuel inlet valve in the float chamber, a vertical spray nozzle connecting the float chamber with the air inlet chamber centrally positioned with relation to the float in the float chamber and with relation to the carbureting tube, a puppet valve mounted in the

spray nozzle, a deflector head on said valve, and means for regulating the lift of the valve to control the amount of fuel discharge.

4. A carbureter comprising a mixture chamber, an air inlet chamber, a plurality of ports through which the air is admitted, a spring-actuated valve closing said ports, means for adjusting the tension of said spring-actuated valve, a float chamber surrounding the air inlet chamber, a throttle valve in the mixture chamber having a plurality of ports, a carbureting tube connecting the throttle valve with the air inlet chamber, means for adjusting said tube with relation to the ports in the throttle valve to increase or decrease the port area, a vertically disposed, automatically controlled fuel inlet valve in the float chamber, a vertical spray nozzle connecting the float chamber with the air inlet chamber centrally positioned with relation to the float in the float chamber, and with relation to the carbureting tube, a puppet valve mounted in the spray nozzle, a deflector head on said valve, means for regulating the lift of the valve to control the fuel discharge, said means comprising an adjustable stop, and means operable from the outside of the carbureter for controlling the position of said stop.

5. A carbureter comprising a mixture chamber, an air inlet chamber, a plurality of ports connecting the air inlet chamber with the outside atmosphere, a spring-actuated valve to close said ports, means for adjusting the tension of the valve spring, said means comprising a washer upon which said valve spring is carried, a strap having an annular collar upon which the washer is mounted, a hollow threaded rod having a collar by which the strap is hung, a wheel for turning said rod, a float chamber surrounding the air inlet chamber, a throttle valve in the mixture chamber having a plurality of ports, a carbureting tube connecting the throttle valve with the air inlet chamber, means for adjusting the position of said tube with relation to the ports in the throttle valve to increase or decrease the port area, a vertically disposed, automatically controlled fuel inlet valve in the float chamber, a vertical spray nozzle connecting the float chamber with the air inlet chamber centrally positioned with relation to the float in the float chamber, and with relation to the carbureting tube, a puppet valve mounted in the spray nozzle, a deflector head on said valve, means for regulating the lift of the valve to control the fuel discharge, said means comprising an adjustable stop, and means for controlling the position of said stop.

6. A carbureter comprising a mixture chamber, an air inlet chamber, a plurality of ports connecting the air inlet chamber with the out-

side atmosphere, a spring-actuated valve to close said ports, means for adjusting the tension of the valve spring, said means comprising a washer upon which said spring is carried, a strap having an annular collar upon which the washer is mounted, a hollow threaded rod having a collar by which the strap is hung, a wheel for turning said rod, a float chamber surrounding the air inlet chamber, a throttle valve in the mixture chamber having a plurality of ports, a carbureting tube connecting the throttle valve with the air inlet chamber, means for adjusting the position of said tube with relation to the ports in the throttle valve to increase or decrease the port area, a vertically disposed, automatically controlled fuel inlet valve in the float chamber, a vertical spray nozzle connecting the float chamber with the

air inlet chamber centrally positioned with 20 relation to the float in the float chamber, and with relation to the carbureting tube, a puppet valve mounted in the spray nozzle, a deflector head on said valve, means for regulating the lift of the valve to control the 25 fuel discharge, said means comprising an adjustable stop, means for controlling the position of said stop, and means independent of the float valve for adjusting the gasoline level with relation to the spray nozzle. 30

In testimony whereof I have hereunto set my hand in the presence of two subscribing witnesses.

JOHN AMBROSE DAVIS.
